CLAIM

The ornamental design for a CO₂-powered grease gun, as shown and described.

DESCRIPTION

FIG. 1 is a front, top and side perspective view of the CO₂-powered grease gun showing our new design;
FIG. 2 is a front elevational view thereof;
FIG. 3 is a rear elevational view thereof;
FIG. 4 is a side elevational view thereof, the side opposite being a mirror image of the side shown in FIG. 4;
FIG. 5 is a top plan view thereof; and,
FIG. 6 is a bottom plan view thereof.

FIG.1.

FIG.6.

FIG.4.

FIG.2.

FIG. 3.

FIG. 5.
